DOOR BRACE

Robert L. Long, Dallas, Tex., assignor to
E. C. Paige, Dallas, Tex.

Application January 8, 1949, Serial No. 129

Term of patent 14 years

(Cl. D54—2)

To all whom it may concern:

Be it known that I, Robert L. Long, a citizen of United States of America, residing at Dallas, in the county of Dallas and State of Texas, have invented a new, original, and ornamental Design for a Door Brace, of which the following is a specification, reference being had to the accompanying drawing, forming part thereof.

In the drawing

Fig. 1 is a side elevational view of a door brace, showing my new design;

Fig. 2 is an edge elevational view of the door brace, taken from the left side of the door brace, as shown in Fig. 1; and

Fig. 3 is an edge elevational view of the door brace taken from the right side of the door brace as shown in Fig. 1.

I claim:

The ornamental design for a door brace, as shown.

ROBERT L. LONG.
